UNITED STATES PATENT OFFICE.

MILTON C. NILES, OF OAK PARK, ILLINOIS.

RAIL-JOINT.

SPECIFICATION forming part of Letters Patent No. 501,093, dated July 11, 1893.

Application filed June 14, 1892. Serial No. 436,676. (No model.)

To all whom it may concern.

Be it known that I, MILTON C. NILES, a citizen of the United States, residing at Oak Park, in the county of Cook and State of Illinois, have invented certain new and useful Improvements in Rail-Joints, of which the following is a full, clear, and exact specification.

My invention relates to that class of joints in which the rails are supported by means of a base-plate or chair clamped to the under sides of the foot flanges thereof by means of clamps taking their bearing upon the upper sides of the foot flanges; and the object of my invention, generally stated, is to provide a rail joint that shall be simple of construction and easy of manufacture and will firmly, but elastically, support the rails at their meeting ends, without necessitating the puncturing of the rails, or otherwise altering their present form.

More particularly, one of the important objects of my invention is to employ truss plates of different depth or vertical diameter, and consequently, of different strength, on opposite sides of the rails, and at the same time proportionately distribute the pressure or strain between the two plates.

A further important object of my invention, is to bind the truss plates in place and at the same time cause them to lean toward the rails, by the vertical pressure employed for supporting the rails.

With these ends in view, my invention consists in certain features of novelty in the construction, combination and arrangement of parts, by which the said objects and certain other objects hereinafter described are attained, as fully explained with reference to the accompanying drawings and more particularly pointed out in the claims.

In the said drawings,—Figure 1, is a vertical transverse section of a rail having my improved joint applied thereto, taken on the line 1, 1, Fig. 2. Fig. 2, is a plan view thereof, on a smaller scale. Fig. 3, is a perspective view of the same. Fig. 4, is a longitudinal sectional view, taken on the line 4, 4, Fig. 1. Fig. 5, is a view similar to Fig. 1, on a smaller scale showing a slight modification in the arrangement of the vertical bolts and also illustrating brace-plates in dotted lines. Fig. 6, is a transverse sectional view of a portion of

my joint, illustrating a modified form of truss-plate, which will be hereinafter explained, and Fig. 7, is a perspective view of a still further modification of the same.

In the drawings, wherein like signs of reference indicate like parts throughout the several views, 1, are the rails, of the ordinary or any suitable construction, upon whose foot flanges, 2, are supported vertically arranged truss-plates, 3, 4, one on each side, as usual in rail joints. Passing under the rails at the point where they come together, is a base-plate or chair, 5, which is provided at both sides with upturned flanges, 6. Supported upon the upper edge of each of the truss-plates, 3, 4, is an angle iron or plate, 7, through which and the base-plate or chair 5, pass a number of bolts, 8, 8^a which are so arranged as to come against the outer edges of the rail flanges, as shown more clearly in Fig. 1, and thus hold the rails against transverse or lateral movement. These bolts, serve to bind the base-plate or chair, 5, firmly against the under sides of the rail flanges, and in doing so, clamp the truss plates 3, 4, firmly upon the upper sides of such flanges, and thus render downward movement of the rails at their junction impossible, without bending the truss-plates 3, 4, transversely of their vertical areas, and as they may be made of great depth, it will be seen that a joint thus constructed possesses great strength. It will, of course, be understood, that it is immaterial how high the edge of the joint extends on the outer side of the rail, or on that side of the rail where the wheel flanges do not come, so long as it does not extend above the rail, so as to be struck by the edge of the tread; and in order that this space may be fully utilized to the best advantage for the accommodation of a strengthening medium, I extend the truss-plate, 3, upward a considerable distance above the top of the truss-plate 4, so as to greatly increase the vertical diameter of its cross-section, and, as will be understood, greatly increases its strength over that of the truss 4. This inequality of the two truss-plates, 3, 4, of course, renders the joint stronger on one side than on the other, and ordinarily, this difference in strength on the two sides of the rails, would result in an uneven or tipping movement thereof, in case

the weight of the rolling stock should be sufficient to depress them at the joint, but, in order that the weaker sides of the joint, or the weaker truss-plate 4, may be relieved of 5 a portion of the strain, and the truss-plate 3 caused to sustain such portion, so as to distribute the pressure between the two truss-plates proportionately to their respective strengths, I provide the base-plate, or chair 5, 10 with a boss or fulcrum, 9, arranged lengthwise of the rails, but nearer the plate 3 than the plate 4, so that the power of the bolt 8^a will act upon the plate 3 through a longer leverage than that through which the bolt 8 acts upon 15 the plate 4. The truss-plates, 3, 4, are provided throughout their lower edges with toe flanges, 10, which rest upon the inclined surface of the rail flanges, and strengthen the truss-plates laterally, and at the same time improve 20 their bearing surfaces. The truss-plates, 3, 4, rest throughout their height against the vertical bolts, 8, 8^a, and it will be seen, that the act of tightening up such bolts produces a 25 tendency in the truss plates to slide down the inclines of the rail flanges, which, of course, results in their closer engagement with the bolts 8 8^a; and as such bolts are held against outward movement, the truss plates will be prevented from slipping off the rail flanges at 30 their lower edges. With the truss-plates provided with the toe flanges, 10, it is hardly possible that the action of the bolts 8, 8^a could cause the upper edges of the truss-plates to slip inward from under the plates 7, but as a 35 precaution or safe-guard against such inward movement of the truss-plates independently of the plates, 7, I provide the inner edges of the plates 7 with depending lips or lugs, 11, which engage over the upper edges of the 40 truss-plates, as shown, and hold them firmly against the bolts.

In order that there may be no outward movement of the bolts 8, 8^a and plates 7, I provide the latter with depending flanges or 45 wedges, 12, along their outer edges, which engage between the upturned flanges, 6, of the base-plate, and the bolts 8, 8^a, the space between the truss-plates 3, 4, and the wedges 12 being just sufficient to permit of the passage 50 of the bolts, and the wedges 12 being of considerable depth or vertical diameter in cross-section, they will bear at a low point on the bolts, and thus effectually prevent the plates 7 from tipping when the bolts are tightened 55 up. The flanges, 6, of the base-plate, are inclined or wedge shaped, so as to be complementary in shape to the wedges 12, and thus, it will be seen, that as the bolts 8, 8^a are tightened up, the wedges 12 will crowd between 60 the rigid flanges, 6, and the bolts, 8, 8^a, and will cause the bolts a slight tendency to tip inward, which movement will, of course, be also imparted to the truss-plates, 3, 4, causing them to rock or slightly lift on the inner ends 65 of their toe flanges, 10; and in order that this movement of the truss-plates may be further utilized to advantage, a pair of brace-plates

may be interposed between the heads of the rails and the angle formed by each of the truss-plates with its toe flange, as shown in 70 dotted lines in Fig. 5, whereby the upward movement of the toe flange 10 will be transmitted to the heads of the rails for affording them greater support and guarding against their independent lateral movement. But, it 75 should be understood, that the purpose of the inward movement of the bolts 8, 8^a at their upper ends, induced by the wedges, 6, 12, is not simply for supplying motion to the brace-plates, as the joint as a whole, is complete 80 without such brace-plates, this inward movement being mainly for the purpose of counteracting the tendency of the truss-plates 3, 4, to rock outward under the pressure of the bolts 8, 8^a. 85

The truss-plates, 3, 4, may be about the same in length as the ordinary fish plates, or long enough to rest on two ties, while the base-plate or chair, 5, and the plates 7, need be of sufficient length only to extend a short distance along each rail; usually, they are about five inches in length, while the truss-plates are thirty inches in length. 90

The joint as a whole, may be anchored to the ties in any of the well known ways, but 95 I prefer to accomplish this by providing the truss-plates along their lower outer edges with outwardly projecting flanges, 13, in which are formed notches, through which spikes, 13^a, are driven into the cross-ties. This flange, 13, is 100 also cut away, as shown in Fig. 4, so as to form shoulders, 13^b, adjacent to the bolts 8, 8^a; thus preventing the longitudinal movement of the base-plate and parts connected therewith, 105 relatively to the truss-plates.

There may be any desired number of the bolts 8, 8^a, but I have found that two on each side are sufficient, the nuts on the bolts 8, being arranged on the upper ends, while those on the bolts 8^a,—the side of the rails on which 110 the wheel flanges pass—being arranged on the lower ends, the joint being usually tightened by means of the upper nuts.

An advantage in using two bolts on each side, is that each may be passed through or 115 set into an ordinary notch in the edge of the rail flanges, as shown in Fig. 5, thus not only getting the bearing points of the truss-plates, 3, 4, nearer the web of the rail, but anchoring the rails to the joint and preventing them 120 from creeping away from the joint.

The main purpose of the plates 7, it will be understood, is to constitute a flat and firm bearing surface for the heads and nuts of the bolts, 8, 8^a, while at the same time, (by reason of their lips or lugs 11) guarding against the displacement of the truss-plates, 3, 4; and for the sake of convenience of description, I will therefore, hereinafter term them "bearing plates;" but I wish it to be distinctly understood that by that term I do not mean to include the lips or lugs 11, and wedges 12, unless the same are particularly specified. 125 130

As a modification of the truss-plates and

the bearing plates 7, I have shown in Fig. 6, a form in which the truss-plate and the bearing plate are formed integrally. In this instance, the lug or lip 11, is, of course, omitted. The bearing plate 7^a is thicker than in the other form, and the wedge 12^a thereon, is formed by beveling its outer edge, so as to co-operate with the wedge-shaped flange, 6, and perform the functions before described. 5 The bearing plates 7^a, in this instance, may or may not extend throughout the length of the truss-plate, 4.

As a still further modification of the truss-plates, I have shown in Fig. 7, a much simplified form, in which the bearing plates for the bolts 8, 8^a are constituted by vertical wedge-shaped ribs or brackets, 7^b, so arranged as to come one on each side of each bolt, under the head, or nut thereof. With this form, the 15 necessity of punching or boring holes for the bolts is avoided, and the whole truss plate, with the bearing plates or brackets 7^b thereon, may be rolled or drop-forged by one operation.

25 Should the rails be already provided with the ordinary angle-bars or angular fish-plates, the truss-plates, 3, 4, might be supported upon the inclined portions thereof, instead of on the foot flanges of the rails as shown, if it 30 should be desired to employ such angle-irons in conjunction with my improved joint.

Having thus described my invention, what I claim as new therein, and desire to secure by Letters Patent, is—

35 1. In a rail joint, the combination with the rails and a chair or base-plate, of a truss-plate supported on edge on the rail flanges and means for suspending said base plate from the upper edge of said truss-plate, substantially as set forth.

40 2. In a rail joint, the combination with the rails and a base-plate or chair, of a truss-plate supported by the rail flanges and bolts having their bearings upon the upper edge of said truss-plate and supporting the base-plate, substantially as set forth.

45 3. In a rail joint, the combination with the rails and a base-plate or chair, of truss-plates supported by the rail flanges and having their upper edges arranged at a distance from the rail-heads and means for supporting the base-plate from said truss-plates, substantially as set forth.

50 4. In a rail joint, the combination with the rails provided with downwardly and outwardly inclined surfaces; of truss-plates resting upon said inclined surface, a base-plate having upturned flanges, bearing-plates supported by said truss-plates and bearing 55 against said upturned flanges, and means for drawing said bearing plates and the base-plate or chair together, substantially as set forth.

55 5. In a rail joint, the combination with the rails; of a base-plate or chair having upturned flanges, truss-plates supported by the rail flanges, bearing plates supported by said

truss-plates and having a bearing against the flanges of said base-plate or chair, and means for drawing said bearing plates and base-plate 70 or chair together, substantially as set forth.

6. In a rail joint, the combination with the rails; of a base-plate or chair having upturned flanges, truss-plates supported by the rail flanges, bearing plates supported by said truss-plates and having wedges or bevels bearing against the flanges of said base-plate or chair, and means for drawing said bearing plates and base-plate or chair together, substantially 75 as set forth.

7. In a rail joint, the combination with the rails; of a base-plate or chair having upturned flanges, truss-plates supported by the rail flanges, bearing plates supported by said truss-plates and having wedges or bevels adapted 80 to bear against the flanges of said base-plate or chair; and bolts against which said truss-plates bear, for clamping said base-plate or chair and truss-plates on the rail flanges, substantially as set forth.

8. In a rail joint, the combination with the rails; of a base-plate or chair having upturned flanges, truss-plates supported by the rail flanges, bearing plates supported by said truss-plates and having wedges or bevels adapted 85 to bear against said upturned flanges; and bolts passing through said bearing plates and base-plate or chair contiguous to the edges of the rail flanges, substantially as set forth.

9. In a rail joint, the combination with the rails; of a base-plate or chair having upturned beveled or wedge shaped flanges, truss-plates supported by the rail flanges, bearing plates supported by said truss-plates and having bearing against said upturned beveled flanges, 95 and means for drawing said bearing plates and base-plate or chair together, substantially as set forth.

10. In a rail joint, the combination with the rails; of a base-plate or chair having upturned flanges, truss-plates supported by the rail flanges, bearing plates supported by said truss-plates and having the depending lugs or lips 100 11, and downwardly projecting wedges or bevels adapted to bear against said upturned flanges, and means for drawing said bearing plates and base-plate or chair together, substantially as set forth.

11. In a rail joint, the combination with the rails; of a base-plate or chair having upturned flanges, truss-plates supported by the rail flanges and having inturned angle toes, bearing plates supported by said truss-plates and having wedges or bevels adapted to bear 110 115 against the said upturned flanges, and means for drawing said bearing plates and base-plate or chair together, substantially as set forth.

12. In a rail joint, the combination with the rails; of a base-plate or chair having upturned flanges, truss-plates supported by the rail flanges and having inturned angle-toes, brace-plates interposed between said angle toes and the heads of the rails, bearing plates supported by said truss-plates and having wedges 120 125 130

- or bevels adapted to bear against said upturned flanges, and means for drawing said bearing plates and base-plate or chair together, substantially as set forth.
- 5 13. In a rail joint, the combination with the rails; of a base-plate or chair having upturned flanges, truss-plates supported by the rail flanges, bearing plates supported by said truss-plates and having depending wedge 10 shaped or beveled portions adapted to bear against said upturned flanges, and bolts passing through said bearing plates and base-plate or chair and against which said beveled portions bear, substantially as set forth.
- 15 14. In a rail joint, the combination with the rails; of a base-plate or chair having upturned flanges, perpendicular truss-plates supported by the rail flanges, bearing plates supported by said truss-plates and having depending 20 wedges bearing against said upturned flanges, and upright bolts against which the rail flanges and said truss-plates bear, passing through said bearing plates and base-plate or chair, and forming bearings for said depending 25 wedges, substantially as set forth.
- 15 15. In a rail joint, the combination with the rails; having notches in their flanges; of a base-plate or chair having upturned flanges, truss-plates supported by the rail flanges, 30 bearing plates supported by said truss-plates and bearing against said upturned flanges, and bolts passing through said bearing plates and base-plate or chair and being seated in said notches in the rail flanges, substantially 35 as set forth.
16. In a rail joint, the combination with the rails; of truss-plates of differing strength on opposite sides of the rails, a base-plate or chair fulcrumed under the rails and constituting a
- lever, one arm of which lever being longer 40 than the other, and a binding connection between the arms of said lever and truss-plates, substantially as set forth.
17. In a rail joint, the combination with the rails; of truss-plates of differing heights on 45 opposite sides of the rails, a base-plate or chair having a fulcrum located to one side of the center of the rails, and binding connections between said base-plate or chair and truss-plates, substantially as set forth.
18. In a rail joint, the combination with the rails; of truss-plates of differing strength on opposite sides of the rails, a base-plate or chair having upturned flanges and being fulcrumed under the rails, so as to constitute a lever, one 55 arm of which lever being longer than the other, bearing plates supported by said truss-plates and having bearing against said upturned flanges, and binding connections between said truss-plate or chair and bearing 60 plates, substantially as set forth.
19. In a rail joint, the combination with the rails; of truss-plates of differing vertical extent on opposite sides of the rail flanges, bearing plates supported by said truss-plates and 65 having depending wedge-shaped or beveled portions, a base-plate or chair fulcrumed under the rails to one side of the center thereof, and having upturned flanges adapted to engage said depending portions, and upright 70 bolts against which said depending portions and the truss-plates bear, passing through said bearing plates and base-plate or chair, substantially as set forth.
